SUSPENDER FOR GARMENTS

Wilbur R. Dove, Washington, D. C.

Application January 9, 1952, Serial No. 265,559

2 Claims. (Cl. 2-310)

1

The object of my invention is to provide a new and improved device for supporting trousers in such a manner that the suspenders will be covered by the shirt, and the weight of the trousers will be supported from the shoulders at points below the arm pits in the easiest and most natural manner. Another object is to provide means to hold a shirt in place by its overlapping edges so that the shirt will be naturally within a lower garment such as trousers and will not bulge nor work out of position. An additional purpose of this invention is to provide means that will both support a lower garment and hold shirt edges in place, and further to provide such means permitting independent adjustment of both articles of apparel.

My invention will be better understood and further objects and advantages will become apparent by reference to the following detailed description thereof:

Figure 1 is a perspective view of the device; Figure 2 is an enlarged view of Z element 10;

Figure 3 is a partial view of combined elements of the device;

Figure 4 is a partial view of an element of the device;

Figure 5 is a view of wings 12 inserted in the trouser's waistband.

Referring now to the drawings, there is shown in Figure 1, Z element 10, which is a plate having upper and lower horizontal bars with an intermediate connecting bar generally angularly disposed and forming opposed re-entrant side openings in the plate. The plate is attached at the upper bar by conventional means 14 to elongate or longitudinally disposed flexible support 11 which extends beyond each end of the bar to partially encircle a wearer's waist and which is provided with holes 15. Suspender loops 17 are joined together by back strap 19 which is attached to suspender loops 17 by slide clasps 20, and provided with conventional length adjuster 18. Suspender loops 17, provided with conventional length adjusters 18, are attached to hooks 16 in the conventional manner. Hooks 16 are designed to pass through holes 15 in support 11.

Channel plate 13 forms a buckle member to detachably receive a pair of tongues and is attached to the base portion of Z element 10 by conventional means 25.

In addition to the foregoing there is shown in Figure 3, shirt 21, buttons 22, shirt under-lap edge 23, and overlap edge 24. Figure 5 shows flexible wings 12 inserted through slits 28, inside waistband 27 of the trousers. These wings or

elongate tongues are adapted to be inserted into or withdrawn from channel buckle member 13.

The operation of the device, described in the foregoing, may be summarized as follows: Slits 28 are cut in the front edge of each side of waistband 27, from which conventional suspenders' buttons have been removed, and wings 12 are inserted therein, as shown in Figure 5, with the offset ends down. With one hook 16 detached from support 11, the wearer's arms are passed through the loops in suspenders 17, and hook 16 is fastened through hole 15. The wearer then puts on his shirt 21, and buttons it up after passing under lap edge 23 into the upper opening of Z element 10 and the overlap edge 24 through the lower opening of Z element 10 at the approximate trouser waist level desired. The only parts of the device now outside of the shirt are the base of Z element 10, and flexible wings 12, which have been inserted into waistband 27. The wearer then steps into his trousers, inserts the ends of wings 12 into channel plate 13, as shown in Figure 3, and buttons the waistband.

The length of trouser suspension may be regulated by opening the shirt front and moving suspender length adjusters 18. Back strap 19 should be adjusted to the most comfortable position by means of side clasps 20 and length adjuster 18, with the shirt removed. This point is usually across the upper inside corners of the shoulder blades. The shirt may then be pulled up or down, and smoothed across the front before buttoning up the fly.

It will be apparent that when support 11, and wings 12 have been bent to follow the contours of the wearer's body, hooks 16 inserted into the proper holes 15 to place the points of suspension of support 11 somewhat forward of vertical lines from the armpits, the weight of the trousers will be in balance, front and rear, and the waist line will be horizontal, or can be made to hang horizontal, by moving hooks 16 to front or rear holes 15. Then, clearly, the weight of the trousers will hang in a most natural manner beneath the armpits, and no part of the waist of the trousers need press against the wearer's body.

It will also be apparent that the entire device will be covered by the wearer's shirt, and the waistband of his trousers. It will also be apparent that the shirt front will be prevented from coming out of the trousers, and bulging, because the lapped edges of the shirt are held firmly by Z element 10, and each side of the front portion of the shirt is held between support 11 and wings 12 or back of an arm of Z element 10.

Furthermore, it will be clear that flexible wings 12 will support the waistband of the trousers more evenly than conventional suspenders having six widely separated points of support.

Having thus described my invention, what I claim as new, and desire to secure by Letters Patent, is:

1. Combination means to hold trousers and shirt in place comprising a plate formed by upper and lower horizontal bars connected together with an intermediate bar extending from opposed ends of said upper and lower bars to form re-entrant side openings in the plate, a longitudinal flexible support secured to the upper bar of the plate and extending beyond each end of said bar, adjustable suspender loops detachably connected to said support at selected positions along the support, a buckle member secured to the lower bar of the plate and having means to detachably engage a pair of elongate tongues, a pair of elongate tongues extending outwardly from each end of said lower bar, each adapted to be detachably held at one end by said engaging means and at the other end to be received by a trouser waistband, said flexible support and said tongues being disposed and adapted to receive a shirt between them.

2. Combination means to hold trousers and

shirt in place comprising a Z plate formed by upper and lower horizontal bars and an angularly disposed connecting bar forming opposed re-entrant side openings in the plate, an elongate flexible support secured to said upper bar and extending beyond each end of said bar to partially encircle a wearer's waist, suspender loops engaging said support and means to adjustably engage said loops at different positions along a portion of the flexible support the lower bar of the Z plate comprising a channel member to receive a pair of elongate tongues, a pair of elongate tongues adapted to be inserted into and withdrawn from said channel member, the tongues extending outwardly from the ends of said lower bar to partially encircle a wearer's waist and adapted for insertion into a trousers waistband, whereby a shirt and trousers may be held between said elongate support and said tongues.
